COMBINATION NEWSPAPER HOLDER AND BOTTLE COOLER

Peter Schlumbohm, New York, N. Y.

Application December 3, 1956, Serial No. 44,034

Term of patent 14 years

(Cl. D58—26)

FIG. 1.

FIG. 2.

FIG. 3.

FIG. 4.

FIG. 5.

Fig. 1 is a top perspective view of a combination newspaper holder and bottle cooler, showing my new design.

Fig. 2 is another top perspective view thereof. The broken line showing of the bottles in Fig. 2 is for illustrative purposes only.

Fig. 3 is a bottom perspective view thereof.

Fig. 4 is a side elevational view thereof, shown partly in section.

Fig. 5 is a top plan view thereof.

I claim:

The ornamental design for a combination newspaper holder and bottle cooler, as shown and described.
